PARTING STRIP

Carlo Mancini, Stratford, Conn.

Application November 3, 1934, Serial No. 751,357

8 Claims. (Cl. 20—52.4)

This invention relates to new and useful improvements in parting strips for window frames.

An object of the invention is to provide a parting strip of improved construction which will function to prevent rattle of sashes in a frame and which makes for a weather proof window construction and which is closed at its outer side.

Another object is to provide an improved window construction including the mentioned parting strip and means for securing it in place.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a perspective view showing a portion of a window construction incorporating the present invention;

Fig. 2 is a horizontal sectional view through an edge portion of the sashes and one side of the frame;

Fig. 3 is a perspective view of an upper corner portion of the lower sash;

Fig. 4 is a detail sectional view showing the means securing the lower portion of the parting strip in place.

Referring in detail to the drawing the window frame is generally designated 10 and vertically slidable in the frame are upper and lower sashes 11 and 12 which sashes are arranged between inside and outside beads 13 and 14 respectively. The frame 10 includes a head 15 with which we are not particularly concerned and a sill 16 and between the head and sill is a side jamb 17. The lower end of the side jamb 17 is dadoed into the sill 16 as shown at 18a in Fig. 4 and opening through the inner face of the side jamb and extending from the lower end of the side jamb upwardly at least to the head 15 is a groove 18.

A parting strip 19 comprising an elongated body preferably formed of a single piece of sheet metal and substantially rectangular in transverse section is arranged with one side portion within the groove 18 and the parting strip extends from the sill 16 to the head 15. One wall 20 of the parting strip is inwardly bowed as best shown in Fig. 2 and this wall is at the bottom of the groove 18. The side walls 21 and 22 of the strip extend outwardly through the open or front side of the groove 18 and the outer wall of the parting strip comprises inner and outer wall sections 23 and 24 arranged in overlapping relationship as

shown in Fig. 2. Adjacent the wall sections 23 and 24 the side walls 21 and 22 are pressed or off-set outwardly to provide vertically extending beads or ribs 25 and 26. The wall sections 23 and 24 are not secured together but are slideable past 5 one another to permit the side walls 21 and 22 of the strip to yield toward and from one another for a purpose to be described.

The upper sash 11 includes a lower or meeting rail 27, an upper rail 28 and a vertical side rail 29 while the lower sash 12 includes a lower rail 30, a meeting rail 31 and a vertical side rail 32. In the opposed faces of their vertical rails 29 and 32, the upper and lower sashes are provided with vertically extending grooves 33 and 34 15 which grooves are of a size and so located as to accommodate the beads or ribs 25 and 26 on the sides of the parting strip 19. This is as best shown in Fig. 2. The meeting rail 27 of the upper sash has a laterally projecting portion 35 20 which portion projects inwardly or toward the inner sash while the meeting rail of the inner or lower sash 12 has a lateral portion or over-hanging portion 36 extending or projecting outwardly or toward the upper sash. 25

When the sashes are in closed positions the portions 35 and 36 inter-lock or abut to provide a weather tight joint. The projecting portions 35 and 36 do not extend for the lengths of the meeting rails but have their ends cut away as at 30 37 in Fig. 3 and the shoulders 37 overlie the overlapping wall sections 23 and 24 of the parting strip and maintain the outer wall section 24 against the inner wall section 23. With this construction and with the engagement of the 35 sashes with the beads 25 and 26 of the parting strip the latter is held in place in the groove 18 and the wall section 24 of the parting strip is held against the wall section 23 so that said sections slide one on the other and the entrance 40 of dust or rain into the parting strip is prevented.

To prevent removal of the parting strip by person at the outer side of the house the lower end of the parting strip is held within the groove 18. This prevents the removal of the parting strip so 45 as to permit of removal of a sash as might be attempted in an effort to burglarize the house. As shown an opening or hole 38 is provided in the sill 16 opening through the bottom of the dado 18a in line with the groove 18 in the side jamb 50 17. A pin 39 which may be a short section of a dowel rod or of metal or the like has its lower end inserted into the hole 38 and is of such length as to extend above the upper side of the sill 16 and its upper end is located in the groove 18. When 55 the parting strip is being positioned the sashes are not in place and the lower end of the parting strip is telescoped over the upper end of the pin 39 and the size and location of the parts is such that the upper end portion of the pin engages the 60

rear wall 20 of the parting strip and maintains said wall against the bottom wall of the groove 18. It will be apparent that the pin 39 is concealed by the parting strip and that it will prevent outward movement of the lower end of the parting strip with respect to the groove 18.

It should now be understood that the parting strip 19 is secured in the groove 18 without the use of screws or other means perforating the strip and that the strip is held in place by engagement of its side walls 21 and 22 with the side walls of the groove, if the strip is permitted to expand to that extent, and that the strip is further held in place by engagement with the sashes 15 and particularly with the shoulders 37 at the ends 20 of the meeting rails of the sashes and that the lower portion of the strip is secured by the pin 39 engaging the rear wall of the strip. Since the forward wall sections 23 and 24 of the strip are 25 slideable by or on one another it will be understood that the strip is yielding or resilient and that its side walls 21 and 22 may yield toward and from one another so as to maintain their beads 25 and 26 in the grooves 33 and 34 in the vertical 30 sash rails and that such being the case the parting strip has weather-tight engagement with the sashes and will also prevent the sashes from rattling in the frame. The overlapping wall sections 23 and 24 of the strip completely close its outer side and prevent the entrance of dust or rain.

Having thus set forth the nature of my invention, what I claim is:

1. In a window construction including a frame having vertical side jambs, a sill and a pair of sashes vertically slideable between said side jambs, one of said side jambs having a groove in its inner face, a parting strip comprising an elongated hollow body substantially rectangular in transverse section and having a portion received in said groove with its inner wall at the bottom of the groove, said strip having its opposite wall comprising two sections overlapping and slideable past one another to permit the other side walls of the body to yield toward and from one another, and a means projecting upwardly from the sill into the body and maintaining the lower portion of the inner wall of the body within the groove.

2. In a window construction including a frame having vertical side jambs, a sill and a pair of sashes vertically slideable between said side jambs, one of said side jambs having a groove in its inner face, a parting strip comprising an elongated hollow body substantially rectangular in transverse section and having a portion received in said groove with its inner wall at the bottom of the groove, said strip having its opposite wall comprising inner and outer sections overlapping and slideable on one another to permit the other side walls to yield toward and from one another, and said sashes including portions engaging the outer of said overlapping wall sections and maintaining the body in place in the groove and maintaining the said outer section in engagement with the inner section.

3. A parting strip comprising an elongated hollow metal body substantially rectangular in transverse section including an inner wall adapted to be received in a groove in a side jamb of a window frame, said body including outwardly extending flat parallel side walls yieldable toward and from one another about axes represented by their connections with the inner wall, and said side walls adjacent their outer edges each having an outwardly pressed portion providing a bead.

4. In a parting strip comprising an elongated hollow metal body substantially rectangular in transverse section and including an inner wall to be received in a groove in a side jamb of a window frame, said body including outwardly extending side walls and an outer wall comprising a pair of overlapped wall portions slideable past one another to permit the side walls of the body to yield toward and from one another, and said inner wall bowed toward said outer wall for substantially its entire length. 5

5. A parting strip comprising an elongated hollow metal body substantially rectangular in transverse section and including an inner wall adapted to be received in a groove in a side jamb of a window frame, said body including an outer wall comprising a pair of overlapped wall sections slideable past one another, and said body including outwardly extending flat parallel side walls carrying said outer wall sections and each having an outwardly pressed bead to be received in grooves in the side rails of window sashes. 10

6. A parting strip comprising an elongated hollow metal body substantially rectangular in transverse section and including an inner wall to be received in a groove in a side jamb of a window frame, said body including an outer wall comprising a pair of overlapped wall portions slideable on one another, and said body including outwardly extending flat parallel side walls carrying said outer wall sections and movable toward and from one another by flexing about their connections with the inner wall. 20

7. In a window construction including a frame having vertical side jambs, a sill and a pair of sashes vertically slideable between said jambs, one of said jambs having a groove in its inner face, a parting strip comprising an elongated hollow body substantially rectangular in transverse section and including inner and outer and side walls and having a portion received in said groove with its inner wall at the bottom of the groove, said strip having its outer wall comprise inner and outer sections overlapping and carried by the side walls and slideable on one another to permit the side walls to yield toward and from one another, and said side walls flat and of substantially the same width and free and engaging side walls of the groove and opposed faces of the sashes whereby both side walls may pivot from the points of their connections with the inner wall and said sections will not bind on one another. 40 45 50

8. In a window construction including a frame having vertical side jambs, a pair of sashes vertically slideable between said jambs, one of said jambs having a groove in its inner face, a parting strip comprising an elongated hollow body substantially rectangular in transverse section and including inner, outer and side walls and having a portion received in said groove with its inner wall at the bottom of the groove, the outer wall of said strip comprising inner and outer sections overlapping and carried by the side walls and slideable past one another to permit the side walls to yield toward and from one another, said sashes 60 having vertical grooves in their opposed faces, outwardly pressed beads on said side walls of the body adjacent the outer edges thereof, and the outer portions of said side walls beyond the groove lying flat against the sashes and said beads entering the grooves in the sashes whereby seals are formed between the sides of the strip and the sashes. 65 70 75
